COMBINATION STEP AND WALL LADDER

Carl J. Miller, Rochester, N. Y.

Application May 14, 1947, Serial No. 747,981

9 Claims. (Cl. 228—23)

1

The present invention relates to a combination step and wall ladder and more particularly to a step ladder which may be readily converted into a wall ladder or vice versa.

While step ladders and wall ladders are individually well known, each type of ladder has its limitations for use so that heretofore both kinds of ladders had to be kept on hand for the variety of requirements arising in domestic and/or industrial establishments.

A primary object of the present invention is the provision of a combination step and wall ladder capable of use as a step ladder or as a wall ladder and easily changed from one type of ladder to the other.

Another objective of the invention is the provision of a ladder assembly comprising two ladder members hinged to each other and an extension on one of said ladder members for engaging the other ladder member when said members are in substantial alignment.

A further object is the provision of a ladder assembly having two hinged ladder members, an extension on one of said ladder members, and a latch means on the other of said ladder members for engaging said extension and maintaining said members in substantial alignment.

Still another object of the invention is the provision of a ladder assembly having two hinged ladder members, a brace member operatively connected therebetween, and a latch means on one of said ladder members and permitting disconnection of said brace member from one of said ladder members.

A still further object is the provision of a ladder assembly having two hinged ladder members, a brace member and an extension member therebetween, and a pair of latch means simultaneously operable to release said brace member or said extension member for converting said ladder assembly from a step ladder to a wall ladder or vice versa.

Other and further objects of the present invention will be suggested to those skilled in the art by the description which follows.

The aforementioned and other objects of the invention are embodied in a ladder assembly comprising a front ladder member, a rear ladder member hinged thereto, a brace member operatively connected between said ladder members, an extension on one of said ladder members and engaging the other ladder member when said members are in substantial alignment, a latch means operative to disconnect said brace member, a second latch means for engaging said ex-

2

tension and maintaining said ladder members in substantial alignment, and a manually operable means connected to both of said latch means for operation to disengage the same and for normally urging both of said latch means to engaging positions. The useful and operative arrangements and combinations of the above-mentioned elements are set forth in the appended claims.

10 Reference is hereby made to the accompanying drawings wherein like reference characters designate the same or similar elements and wherein:

Fig. 1 is a side elevation of the ladder assembly of the invention as a step ladder.

15 Fig. 2 is a front elevation of my ladder assembly as a step ladder.

Fig. 3 is a side elevation of my ladder assembly in closed or folded position.

20 Fig. 4 is a side elevation of the ladder assembly of the invention with its halves in substantial alignment.

Fig. 5 is a fragmentary plan elevation of the central portion of my ladder assembly as a wall ladder.

25 Fig. 6 is fragmentary longitudinal cross-section through a side rail of the front ladder member showing the details of two latch means and manually operable means therefor.

Fig. 7 is a fragmentary front elevation of a 30 front ladder member with the front wall of the side rail cut away.

Fig. 8 is a transverse cross-section taken on the line 8—8 of Fig. 1.

Fig. 9 is transverse cross-section through a 35 modified formation of the side rail of the front ladder member as though taken on the line 9—9 of Fig. 1.

Fig. 10 is a fragmentary perspective view of the abutment on the pail shelf.

40 In the illustrated embodiment of the invention, the ladder assembly is essentially composed of a front ladder member, a rear ladder member, a hinge connection therebetween, and an extension on one of said ladder members, extending beyond

45 said hinge connection in folded position of said members, and engaging the other ladder member when said members are swung into substantial alignment. Preferably, a latch means is provided on said other ladder member for engaging and holding said extension and said ladder members in substantial alignment. Also, a brace means, preferably in the form of a pail shelf, is operatively connected between said ladder members and a second latch means allows disconnection 50 of said brace means from one of said ladder members.

members. For convenience, a manually operable means is connected to both of said latch means for simultaneous operation thereof and said latch means and/or said manually operable means are biased by gravity or by other means normally to move both of said latch means to engaging positions. Other specific advantages and features of the ladder assembly will be pointed out in the detailed description to follow.

The front ladder member comprises in rather conventional fashion a pair of side rails 10 and 11 held in parallel spaced relation by a plurality of steps 12. Preferably, said side rails 10 and 11 are composed of sheet or tubular metal such as aluminum, steel or other light and/or high strength metal or metal alloy. Also said side rails 10 and 11 are formed by known techniques into a hollow section having parallel side walls 13 and 14 and having rounded front and rear edges 15 and 16, such as shown in Figs. 8 and 9. Other sections for the side rails 10 and 11 suitable for the purposes of the invention will be recognized by those skilled in the art.

The steps 12 may also be formed from any suitable sheet metal and preferably have rolled front and rear edges 17 and 18, the tread 19 therebetween being deformed to strengthen the step 12 and to prevent slipping. Each step 12 has at each end a projection 20 which extends into the interior of the side rail for deformation, as by riveting, against the inner face of side wall 13 as shown for the lower step 12 in Figs. 6 and 7 or which extends completely through the side rail for deformation, such as riveting, against the outer surface of side wall 14, see upper step 12 in Fig. 7.

A top step member 21 is mounted at the top of said front ladder member and is preferably provided with deformed or rolled edges including a rear edge 22 which is provided with a pair of notches 23 and 24 for a purpose later to be described. At each end of top step member 21, a pair of plates 25 and 26 have their top edges fastened to step member 21 as by flanging said edges of the plates 25 and 26 and bending thereover the end edge of said step member 21. Said plates 25 and 26 are deformed so as to be complementary to and engage the side walls 13 and 14 of side rails 10 and 11, see particularly Fig. 8, and a pair of rivets 27 fasten said plates 25 and 26 to the tops of said side rails 10 and 11. As best shown also in Fig. 8, said plates 25 and 26 are also cupped to strengthen the sections for bearings 28 and 29.

A rear ladder member is composed also in rather conventional fashion of a pair of side rails 30 and 31 held in parallel spaced relation by a plurality of rounds 32. As before the side rails 30 and 31 and rounds 32 are composed of sheet or tubular metal or metal alloy having great strength and comparatively light weight. Preferably, said side rails 30 and 31 have rounded or circular front and rear edges as illustrated and the rounds 32 are hollow tubes extending through said side rails 30 and 31 with the ends of said tubes spun over against the outer walls of said rails 30 and 31.

Said front and rear ladder members are pivotally connected to each other as by a hinge connection now to be described. For such purpose, each side rail 30 and 31 of the rear ladder member has its outer wall circularly deformed inwardly to form a cup 33 and has its inner wall circularly deformed inwardly to form a cup 33' which rests in the bearing 28 or 29. Bolts, such

as bolt 34, extend through both of cups 33 and 33' and through each cup bearing 28 and 29 for threaded or similar engagement by nuts 35 and 36, see Fig. 2. As a result, the front and rear ladder members are hinged together about an axis adjacent the upper ends thereof and may be folded adjacent each other or swung into substantial alignment with each other.

An extension member is mounted on one of said ladder members and engages the other ladder member when both ladder members are in substantial alignment. Such an extension member may be composed of a single side arm extending from one of the side rails of said one ladder member, a pair of side arms extending from both of the side rails of a ladder member, or may include a cross-bar between a pair of side arms. Side arms 37 and 38 are illustrated as being integral with and extending from side rails 30 and 31 but it is obvious said side arms 37 and 38 may be supplied as an attachment for connection to the side rails 30 and 31 in any suitable manner. Said side arms 37 and 38 are each formed so as to permit movement of the ladder members into alignment as by outward lateral offsets 39 and 40. A cross-bar 41 extends between side arms 37 and 38 to provide rigidity to the extension member and to constitute lateral inward off-set portions for engaging the other ladder member. Said cross-bar 41 may be covered with a tube 42 of rubber or like material.

The front edges of the side rails 10 and 11 are each respectively provided with notches 43 and 44 which are located to receive the extension member and more particularly the cross-bar 41 when the ladder members are moved into substantial alignment, see Fig. 4. In this position, the ladder assembly can be used as a wall ladder or in place of an extension ladder.

In order to maintain the ladder members in their position of substantial alignment, a latch means is provided to engage and hold said extension member. Most conveniently and for greatest effectiveness such latch means is provided adjacent one or both of notches 43 and 44 in the side rails 10 and 11. Such a latch means preferably comprises a latch plate 45 pivotally mounted on a pin 46 riveted to the inner face of side wall 14 of side rail 10 and having a nose portion 45' and a locking tongue 47 with a strike face 48. Said strike face has a flat portion for closing the end of notch 43 and/or notch 44 and a slight inward radius near the end of the face will improve the automatic operation of the latch means later to be described. The locking tongue 47 on latch plate 45 biases the same by gravity in a counterclockwise direction in Fig. 6 but such bias may be obtained by other means if desired. The latch plate 45 is pivoted and arranged such that engagement of said strike face 48 thereof by the cross-bar 41 will rotate said latch plate 45 in a clockwise direction and permit said cross-bar 41 to enter into and be seated in notch 43 whereupon the gravity bias on the latch plate 45 returns it to the position shown and locking tongue 47 engages and holds said cross-bar 41 within notch 43. A similar latch means for engaging the cross-bar 41 may be placed within side rail 11 adjacent notch 44 also to hold said cross-bar 41 therein. At the same time, side rails 30 and 31 of the rear ladder member are within and engaging the notches 23 and 24 in the rear edge of top step member 21 so that the two ladder members are rigidly and securely held and positioned with respect to each other and any rela-

tive lateral movement therebetween is substantially eliminated.

As seen clearly from Fig. 1 the side rails 30 and 31 of the rear ladder member each have an angular bend 30' adjacent the hinge connection and the side arms 37 and 38 each have a similar but reverse bend, such as bend 37', adjacent the hinge connection. Such angular bends have two advantages, first the bends such as 30' in the side rails 30 and 31 permit a compact relationship thereof to the side rails 10 and 11 in folded position of the ladder members and secondly the effect of two bends is combined to allow the two ladder members to assume more nearly a position of direct alignment in extended position of the ladder members.

When the ladder assembly of the invention is to be used as a step ladder, the two ladder members are moved to the position shown in Fig. 1 and a brace member in the form of a pail shelf is operatively connected therebetween. Such pail shelf comprises a pair of side arms 49 and 50 held in parallel spaced relation by a pair of cross-straps 51 and 52 forming the platform of the pail shelf, a cross-bar 53 extending between the opposite ends of arms 49 and 50, and a tube 54 fastened at each end to the center portions of arms 49 and 50. A tie bolt 55 extends between side rails 30 and 31 and through said tube 54 so that the pail shelf is free to rotate between said rails 30 and 31. Said cross-bar 53 is longer than the normal spacing between the inner and opposed walls of the side rails 10 and 11 of the front ladder member and between the inner and opposed walls of side rails 30 and 31 of the rear ladder member. Said pail shelf is balanced so as to swing normally into a vertical position with the end carrying straps 51 and 52 lowermost.

Such vertical position of the pail shelf will cause it to assume a more convenient or out-of-the-way position when the ladder members are in the extended position shown in Fig. 4 because the cross-straps 51 and 52 are on the far side of side arms 49 and 50 and there is minimum interference with a person standing on top step 21 or stepping on tube 54 or the round 32 just above it. An abutment and fastening means is provided between the pail shelf and one or both of the side rails of the rear ladder member. Such abutment and fastening means is preferably arranged to engage the side rail when the pail shelf is swung to a position adjacent the side rails 30 and 31 and yet readily releasable and permitting movement of the pail shelf in a clockwise direction from its position of engagement. Such an abutment and fastening means may be supplied in any of several ways and conveniently comprises a stirrup member 56 fastened to either or both of cross-straps 51 and 52 preferably by means of the rivets 57 which also fasten cross-strap 52 to the side arms 49 and 50. Said stirrup member 56 is preferably in the form of a U-shaped leaf spring and is located and formed so that the bottom curved surface thereof engages the rounded surface of the rear edge of side rails 30 and 31 of the rear ladder member just prior to the abutment of the ends of cross-bar 53 against the front edges of side rails 30 and 31 at which time the end of member 56 frictionally engages the faces of side rails 30 and 31.

When the ladder assembly is swung open and the ladder members are in substantial alignment, the heavier end carrying the cross-straps 51 and 52 of the pail shelf swings downwardly and a slight pressure thereon will cause engage-

ment of stirrup members 56 with the faces of side rails 30 and 31 which will eliminate excessive swinging movement of the pail shelf. Such resilient clamping is only sufficient to overcome the gravitational tendency of the pail shelf when the ladder members are folded and the cross-bar 53 is held slightly away from the front edges of side rails 30 and 31 for re-entry into recesses 59 in the rails 10 and 11 of the front ladder member.

The cross-bar 53 of the pail shelf is arranged for operative engagement with the front ladder member as by being longer than the spacing between the inner walls, one of which is side wall 13, of the side rails 10 and 11. Said inner walls 13 of side rails 10 and 11 are both provided with an elongated recess 59, see Figs. 1 and 6. Said recess 59 has an open end 60 located at the rear edge of one or both of side rails 10 and 11 and located for entry of the ends of cross-bar 53 when the ladder members are in the closed or folded position thereof. Said elongated recess 59 has a closed end 61 located at a position to limit the opening or unfolding movement of the ladder members to an extent to give good stability to the ladder assembly when used as a step ladder as illustrated in Fig. 1.

The elongated recess 59 may also be provided as deformed or depressed track 62 in the inner, facing walls of the side rails 10 and 11. Such a track 62 is shown in Fig. 9 and is arranged so that the walls thereof form the elongated recess 59 with an open end and a closed end. Also the engaging ends of the cross-bar 53 may be provided with rollers 63 mounted in each end thereof, see Fig. 9, and may be individually mounted on the ends of side arms 49 and 50.

A latch means is preferably located adjacent the lower end 60 of the elongated recess 59 so that the brace means is normally held within elongated recess 59. Such a latch means comprises a latch plate 64 pivotally mounted on the side rail 10 by a pin 65, has a locking tongue 66 normally closing said recess 59, and has a nose portion 67 for engaging a part of the side rail 10 and limit the rotation of said latch plate 64. A strike surface 68 is provided along the outer edge of locking tongue 66 and is shaped so that engagement by the ends of cross-bar 53 will swing latch plate 64 out of the path of the elongated recess 59 to permit entry of said cross-bar 53 thereto. Also the latch plate 64 is arranged and balanced so that the normal position is that shown in Fig. 6.

Although both latch means are automatically displaced for entry respectively of cross-bar 41 into notches 43 and 44 and the ends of cross-bar 53 into the elongated recesses 59, it is necessary to provide manually operable means for retracting said latch means and, if desired, for further biasing said latch means normally to locking position. The manually operable means may be provided in any way so as to accomplish the aforementioned purposes and may comprise a connecting rod 69 pivotally connected at one end to the latch plate 64 by a pin 70 and at its other end to the latch plate 64 by a pin 71, hand bar 72 having off-set ends 73 and 74 extending through and journaled in the inner and facing walls of the side rails 10 and 11, a disc 75 fastened on the ends, such as off-set end 73, of hand-bar 72 within side rail 10, and a second connecting rod 76 pivotally connected at one end eccentrically to disc 75 by a pin 77 and at the other end to pin 71 on latch member 64. Operation of hand bar 72 in a clockwise direction as

seen from Fig. 6 will rotate said disc 75 and latch plates 64 and 45 also in a clockwise direction and move locking tongues 66 and 47 out of the paths respectively of the ends of cross-bar 53 or of the cross-bar 41. Such movement of the latch means for manual release thereof is limited by the abutment of nose portions 45' and 67, respectively, against the opposite edge walls of the side rail 10. Also said manually operable means and the hand bar 72 thereof are arranged so as to augment the biasing of the two latch means to locking positions but yet not sufficient to prevent the automatic and momentary opening of the latch means respectively by the cross-bars 41 or 53.

Feet 18 composed of rubber or other suitable material may be fitted onto the lower ends of the side rails 10, 11, 30 and 31 to improve the traction of said ends with the floor, wall or other surface.

The operation of the ladder assembly of the invention will now be described and is as follows:

The ladder assembly is normally stored with the ladder members in closed or fully folded position as shown in Fig. 3. Preferably, the brace member remains operatively connected to the other ladder member with the ends of cross-bar 53 within the elongated recesses 59 and maintained therein by the latch means including latch plate 64 which is biased to locking position.

The ladder assembly may be used as a step ladder in the regular way by spreading the front and rear ladder members to the extent permitted by the brace means whereupon the pail shelf is swung into horizontal position in the usual fashion. In this position the cross-bar 41 of the extension member is above the top step member 21 and provides a useful addition to the step ladder, said cross-bar 41 being capable of serving as a hand rail for a person climbing the step ladder and also as steadyng support against the shins of a person standing on said top step member 21.

An important and unusual feature of the ladder assembly of the invention is its capability to be converted into a wall ladder. With the ladder members in the closed position shown in Fig. 3, the hand bar 72 of the manually operable means is swung forwardly and upwardly toward the step 12 just above it and in turn the disc 75 and connecting rod 76 are operated to rotate latch plate 64 in a clockwise direction as seen from Fig. 6 and the locking tongue 66 is withdrawn from its normal position across elongated recess 59. The ends of cross-bar 53 may now be swung out of said recesses 59 by rotating the pail shelf in a counterclockwise direction as viewed from Fig. 3 and/or by rotating the rear ladder section in the same direction. The rear ladder member can now be swung about its hinge connections into a position of substantial alignment with the front ladder member. At the same time, the cross-bar 41 of the extension member enters notches 43 and 44 in the front edges of the side rails 10 and 11 and the edges of side rails 30 and 31 enter and engage the notches 23 and 24 in the rear edge of the top step member 21. Four points of engagement are thus provided between the two ladder members to insure ample rigidity therebetween and the weight of a person using the ladder against a vertical wall or other surface increases the pressure on said four points of engagement.

Although the ladder assembly with its members in substantial alignment is self-locking in one direction under conditions of normal use, the extended ladder assembly can be more readily

manipulated or shifted when the members are locked in aligned position. Such locking can be accomplished by manual opening of the latch means and latch plate 45 by the hand-bar 72

5 and manual closing by reverse movement thereof after the cross-bar 41 has entered notches 43 and 44 in the front edges of side rails 10 and 11. However, the opening and closing of the latch means for cross-bar 41 is also automatic. 10 Said latch means including latch plate 45 is normally in the position shown in Fig. 6. As the rear ladder member is swung into substantial alignment with the other ladder member the cross-bar 41 enters slots 43 and 44 and abuts 15 against the strike surface 48 including the inward radius thereon and the pivotal axis of said latch plate 45 are such that further movement of cross-bar 41 swings the latch plate 45 in a clockwise direction until locking tongue 47 opens 20 the remainder of slots 43 and 44 and cross-bar 41 abuts the bottoms thereof and latch plate 45 returns to its normal position with locking tongue 47 engaging and holding the cross-bar 41 within said slots 43 and 44. In this manner 25 automatic unlocking and locking of the latch means for cross-bar 41 has been accomplished.

When it is desired to convert the ladder assembly to a step ladder or fold the ladder members for storage, the hand bar 72 is swung toward the superjacent step 12 to retract the locking tongue 47 and permit the swinging of the ladder members to the closed position as shown in Fig. 3. If it is desired to connect the brace means to the front ladder member, said hand bar 72 may be held in unlocking position and the ends of cross-bar 53 introduced into elongated recesses 59. But it is not necessary manually to hold the latch means including latch plate 64 in open position because that latch means can be automatically opened by the ends of cross-bar 53 in a manner that is quite obvious and very similar to that in which cross-bar 41 automatically operates the other latch means.

30 45 The latch means for cross-bars 41 and 53 may be provided singly or in pairs and may, if desired, be independent of each other and of the other half when provided in pairs. The illustrated embodiment shows and contemplates both 35 latch means provided in pairs and all simultaneously operated but it is well within the scope of the disclosure and of the invention that such latch means can be individually and singly provided and operated.

50 55 Many variations of the ladder assembly shown are possible without departing from the spirit of the invention, the scope of which is defined in the appended claims.

Having now particularly described my invention what I desire to secure by Letters Patent of the United States and what I claim is:

60 65 1. A ladder assembly comprising a front ladder member having side rails in parallel spaced relation and a step member over the tops of said side rails, a rear ladder member having side rails in parallel spaced relation and hinged at one end to said step member, and an extension member having side arms extending from each side rail of said rear ladder member and each 70 laterally and outwardly off-set, and having a cross-bar between said side arms and above said step member in folded and adjacent positions of said ladder members, the side rails of the first-mentioned ladder member each being provided 75 with a recess to receive said cross-bar and the

rear edge of said step member being provided with notches spaced to receive the respective side rails of the rear ladder member when said ladder members are unfolded into substantial alignment.

2. A ladder assembly comprising a front ladder member having hollow side rails in parallel spaced relation, a rear ladder member having side rails in parallel spaced relation and hinged at one end to said front ladder member, an extension member having side arms extending from each side rail of said rear ladder member and having a cross bar between said side arms and above the tops of said ladder members in folded and adjacent positions thereof, the side rails of said front ladder member each being provided with recesses to receive said cross bar when said ladder members are unfolded into substantial alignment, and a latch means within each hollow side rail of the front ladder member and having a portion to engage and hold said cross-bar within said recesses.

3. A ladder assembly comprising one ladder member having side rails in parallel spaced relation and with inner opposed and parallel faces, a second ladder member hinged at one end to the upper end of said one ladder member, and a brace member pivotally mounted upon said second ladder member and having a cross bar at one end thereof parallel to the pivotal axis of said brace member and longer than the space between the opposed faces of said side rails, at least one of said inner faces being provided with an elongated recess, one end thereof being open and located to permit connection and disconnection of the end of said cross-bar in closed position of said ladder members, and the other end of said recess being closed to abut the end of said cross-bar to limit the opening movement of said ladder members.

4. A ladder assembly comprising one ladder member having hollow side rails in parallel spaced relation and with inner and opposed walls, a second ladder member hinged at one end to the upper end of said one ladder member, and a brace member pivotally mounted upon said second ladder member and having a cross-bar at one end thereof and longer than the space between said inner walls, at least one of said inner walls being deformed inwardly to provide an elongated recess for receiving the end of said cross-bar, one end thereof being open and located to permit connection and disconnection of the end of said cross-bar in closed position of said ladder members, and the other end of said recess being closed to abut said end of the cross-bar to limit the opening movement of said ladder members.

5. A ladder assembly comprising one ladder member having hollow side rails in parallel spaced relation and with inner and opposed walls, a second ladder member hinged at one end to the upper end of said one ladder member, a brace member pivotally mounted upon said second ladder member and having a cross-bar at one end thereof and longer than the space between said inner walls, at least one of said inner walls being deformed inwardly to provide an elongated recess for receiving the end of said cross-bar, one end thereof being open and located to permit connection and disconnection of the end of said cross-bar in closed position of said ladder members, and the other end of said recess being closed to abut said end of the cross-bar to limit the opening movement of said ladder members, and a latch means within at least one of said hollow side rails and having a portion normally closing the open

end of said elongated recess and manually operable to open said latch means for disengaging said cross-bar from said recess.

6. A ladder assembly comprising a front ladder member having hollow side rails in parallel spaced relation and with inner and opposed walls, a rear ladder member having side rails in parallel spaced relation and hinged at one end to the upper end of said front ladder member, an extension member having side arms extending from each side rail of said rear ladder and having a cross-bar between said side arms, the front edges of said side rails each being provided with a recess to receive the cross-bar of said extension member when said ladder members are in substantial alignment, a brace member pivotally mounted upon said second ladder member and having a cross-piece longer than the space between said inner walls which are deformed inwardly to provide in each an elongated recess for receiving the respective ends of said cross-piece, one end of each recess being open and located to receive the ends of said cross-piece in closed position of said ladder members, a latch means within each hollow side rail and having a portion movable to close the recesses in the front edges of said side rails, and a second latch means within each hollow side rail and having a portion normally closing the open end of said elongated recess and movable to open said end thereof.

7. A ladder assembly comprising a front ladder member, a rear ladder member, a hinge connection between the ends of said members, a brace member operatively connected between said members for limiting the angular displacement thereof, a latch means on one of said members and operative to permit disconnecting said brace member from one of said ladder members, an extension on one of said ladder members, extending beyond said hinge connection in folded and adjacent positions of said members, and engaging the other ladder member when said members are swung into substantial alignment, a second latch means between said extension and said other ladder member and for maintaining said ladder members in a position of substantial alignment, and a manually operable means connected to both of said latch means and for simultaneous movement thereof to disengaging position.

8. A ladder assembly comprising a front ladder member having hollow side rails in parallel spaced relation and with inner and opposed walls, a rear ladder member having side rails in parallel spaced relation and hinged at one end to the upper end of said front ladder member, an extension member having side arms extending from each side rail of said rear ladder and having a cross-bar between said side arms, the front edges of said side rails each being provided with a recess to receive the cross-bar of said extension member when said ladder members are in substantial alignment, a brace member pivotally mounted upon said second ladder member and having a cross-piece longer than the space between said inner walls which are deformed inwardly to provide in each an elongated recess for receiving the respective ends of said cross-piece, one end of each recess being open and located to receive the ends of said cross-piece in closed position of said ladder members, a latch means within each hollow side rail and having a portion movable to close the recesses in the front edges of said side rails, a second latch means within each hollow side rail and having a portion normally closing the open end

11

of said elongated recess and movable to open said end thereof, and a manually operable means connected to both of said latch means within both of said side rails for simultaneously opening and closing of each.

9. A ladder assembly comprising a front ladder member having hollow side rails in parallel spaced relation and with inner and opposed walls, a rear ladder member having side rails in parallel spaced relation and hinged at one end to the upper end of said front ladder member, an extension member having side arms extending from each side rail of said rear ladder and having a cross-bar between said side arms, the front edges of said side rails each being provided with a recess to receive the cross-bar of said extension member when said ladder members are in substantial alignment, a brace member pivotally mounted upon said second ladder member and having a cross-piece longer than the space between said inner walls which are deformed inwardly to provide in each an elongated recess for receiving the respective ends of said cross-piece, one end of each recess being open and located to receive the ends of said cross-piece in closed position of said ladder members, a latch means within each hollow side rail and having a portion movable to close the recesses in the front edges of said side rails, a second latch means within each hollow side rail and having

10

15

30

12

a portion normally closing the open end of said elongated recess and movable to open said end thereof, and a manually operable means connected to both of said latch means within both of said side rails for simultaneously opening and closing of each, said manually operable means being arranged, when said front ladder member is upright, so that gravity causes movement of said latch means to closed positions.
